GENERAL RAILWAY SIGNAL COMPANY, OF ROCHESTER, NEW YORK

TRAIN-DISPATCHING SYSTEM FOR RAILROADS

Application filed April 20, 1929. Serial No. 356,810.

This invention relates to train dispatching systems, and more particularly to a synchronous selector train dispatching system of the type whereby communication is established 5 between the central dispatcher's office and each way station successively, for effecting the transmission of various indication impulses over a comparatively few line wires.

In a synchronous selector type dispatching system, partial circuits are completed at the dispatcher's office sequentially and in synchronism with other partial circuits at various way stations connected in series therewith, so that indication impulses may be 15 transmitted to a large number of traffic controlling devices, and that indication impulses denoting the progress of trains, commonly called, "OS indications", may be transmitted to the dispatcher's office. These momentarily 20 made circuits may be conveniently called "message channels", with the time required, to successively complete the total number of channels for a particular system, termed the total time cycle.

25 By way of illustration, suppose that a dispatching system is used to control traffic over a single track railroad having twenty passing sidings. If these passing sidings were of considerable length and required a separate 30 way station control apparatus at each end of the passing siding, then there would be 40 way stations. Assuming that the message channels needed for each way station to control the switch machine and signals at each 35 way station and to transmit the OS indication, numbered four message channels, then the total number of message channels for the system would equal 160. Assuming that each message channel requires one-fifteenth of a 40 second for completion and the transfer from one way station to another way station requires two-fifteenths of a second, then the total time cycle of this specific illustration would equal approximately sixteen seconds.

45 Experience in practice has taught, that there is but a small percentage of the total number of message channels set-aside for the transmission of control indications which are actually used for transmitting control indications at any one time. Thus, if the con-

trol indication message channels at a way station, where control indications are to be transmitted, are set up and all other control indication message channels are not set up, then the total time cycle has been considerably 55 reduced.

It is of course understood that the OS indications are very important and necessarily should be transmitted to the dispatcher as soon as possible. Thus, the reduction of a 60 total time cycle assists in this respect.

In a certain type of train dispatching system to which the present invention is particularly well adaptable only one form of OS indication need be transmitted to the dispatcher's office for each way station, namely the condition of occupancy of the detector track circuit. It is further seen that, if a control indication is to be transmitted to a way station at the extreme end of the territory under control of the dispatcher, then as the control is automatically transferred from one way station to the next way station successively, the OS indications may be 65 picked up at each station as the transfer of control is accomplished, thus, the time required for the OS indication message channels is eliminated, as the time required for transferring from one way station to the 70 next way station is sufficient for both the transfer function and for the transmission of an OS indication.

Again assuming the figures as used in the former illustration, the total time cycle now has been greatly reduced as will be presently 85 shown, assume of course that there are no control indications to be transmitted, the total time cycle of the system for picking up all OS indications, or briefly expressed as OS-scanning, may be completed in approximately 90 six seconds. There are now only 120 message channels to be set up for control indications, should every switch and signal on the system under control of the system be desired to be controlled simultaneously. 95 However, in practice there would probably not be more than four or five stations receiving controlling indications during any one total cycle, which has thus been reduced to what might be called a minimum value. 100

In view of the above considerations and others, it is proposed to use in accordance with the present invention, a self stepping synchronous selector system, which is operable through the use of properly designed mechanisms for completing a certain required number of message channels, of which a predetermined number are sequentially set up in each total time cycle, and a certain number for each way station which are sequentially set up for that way station only, when there are indication impulses to be sent to that particular way station. These message channels are to be used for the transmission of indication impulses for controlling the switch machines, signals, de-rails and the like, within the territory over which the system has control. In accordance with the present invention, it is further proposed to transmit a plurality of positive impulses over a transfer circuit including a transfer line wire and common return wire to effect the transfer of the dispatcher's control from one way station to the next successively, with the control given to each successive station after its selecting impulse, and when such control over each way station has been successively set up, then the original starting position shall be attained by a negative impulse. Also, during such time that the system is transferring from one way station to the next way station the GS indication impulses is proposed to be picked up, as each station is successively under control. On the other hand the message channels used for control indication impulses shall be set up only at such time as a control lever has been moved to a new position effecting a control for that particular way station, with such message channels established through the synchronous operation of a group of channel selecting relays at the dispatcher's office and a group of channel selecting relays at the way station to which a control indication impulse is to be transmitted. These groups of relays operating synchronously to set up the control indication message channels effected by the transmission of a plurality of alternate positive and negative impulses over a stepping circuit, including the stepping wire and the common return wire, with each impulse energizing one of the above mentioned relays in the dispatcher's office and one of the above mentioned relays in the way station then under control, during which period of time that exists between the movement of two successive relays, a message channel between the particular way station and the dispatcher's office is set up. Other objects, purposes and characteristic features of the present invention will in part be obvious from the accompanying drawings and in part be pointed out as the description progresses.

65 In describing the invention in detail, ref-

erence will be made to the accompanying drawings, in which:—

Fig. 1A illustrates conventionally the equipment in the dispatcher's office of one specific embodiment of the present invention;

Fig. 1B illustrates conventionally the equipment of the first way station; and, Fig. 1C illustrates conventionally the apparatus at the second way station.

Description of apparatus

In practice a dispatching system may be used to control the switch machines and way-side signals of a large portion of a railway system, possibly including passing sidings, diverging routes, draw bridges, railroad crossings and the like, however, the present invention has for convenience been shown as applied to the apparatus used for effecting the control of traffic at the east and west ends of a passing siding PS (see Figs. 1B and 1C). The passing siding PS is associated with a main track having track sections TK¹, TK² and TK³ of a single track railway system, provided with absolute-permissive-block signaling except at track sections such as TK¹ and TK³ which are under the control of the dispatcher. The track sections TK¹ and TK³ contain track switches TS¹ and TS² respectively, which have associated therewith the usual detector track circuits. Track section TK¹, including a fouling track section FS¹, is inclosed by insulated joints 1 and 2. Likewise the track section TK³, including a fouling track section FS², is inclosed by insulated joints 3 and 4. These track sections TK¹ and TK³ have track batteries 5 and 6 respectively, associated therewith, to supply energy to their respective track relays TR¹ and TR².

The starting signals for the main track and passing siding at the west end of the passing siding PS have been designated SW¹ and SW², respectively, and at the east end of the passing siding PS has been designated SE³ and SE⁴, respectively. At the west end of the passing siding PS is the main line signal and the take siding signal SE¹ and SE², respectively, and at the east end of the passing siding PS is the main line signal and the take siding signal SW³ and SW⁴ respectively.

In the dispatcher's office is preferably located a miniature track layout (see Fig. 1A) corresponding in every detail to the system over which the dispatcher has control. In the particular arrangement shown this miniature track layout includes the passing siding ps and the main line track sections tk¹, tk² and tk³. This miniature track layout has indicating lamps I¹ and I² associated therewith, which if illuminated, indicate the occupancy of the corresponding track circuits, namely the track circuits of track sections TK¹ and TK³ respectively. The switch machine SM¹ associated with the track switch TS¹ at the west end of the passing siding PS is pref-

erably controlled by the switch machine relay SMR¹, which relay is in turn controlled by the lever SML¹ through the medium of the self stepping synchronous selector system herein-after described. Similarly the signals SE¹, SE², SW¹ and SW² are controlled by the signal relay SR¹ and the direction relay DR¹, which are controlled through the medium of the synchronous selector system in accordance with the position of lever SL¹ located in the dispatcher's office. Also, the track switch TS² and the signals SE³, SE⁴, SW³ and SW⁴ are likewise controlled in accordance with their respective control levers SML² and SL² in the dispatcher's office. The relays SMR¹, DR¹ and SR¹ control their respective functions in a manner as fully set forth in the pending application of S. N. Wight, Ser. No. 321,185, filed November 22, 1928.

In the dispatcher's office, there are groups of relays completing the control message channels for the particular way station which a particular group may represent, one of which groups contain the relays 1¹, 2¹ and 3¹, in which the order of the number gives the order of sequential operation for that way station and the order of the exponent gives the order of that particular way station which they represent. Similarly, the group of relays 1², 2² and 3² are the control message channel selecting relays for the second way station, with the reference characters having a like meaning. The energizing circuits for these groups of message channels selecting relays, are repeated by the line relay L⁰ while the particular group to be operated is selected by the master station selector MST. This master station selector MST includes a plurality of circuit selectors M, S and T mounted upon the same shaft and so arranged that a complete cycle of operation is accomplished when the arms of said circuit selectors have operated through 180 degrees. The shaft, upon which the circuit selectors are mounted, is rotated in a clock-wise direction by suitable motor means comprising, an electromagnet E, an armature A, a lever L, a ratchet finger R and a sprocket wheel SP. Associated with the lever L are the contacts 7 and 8. The lever L is biased to an upward position by a spring 9. The biasing force of this spring 9 is sufficient to rotate the circuit selectors M, S and T one step upon energization and de-energization of the magnet E. The spring 10 serves to cause the ratchet lever R to always engage sprocket SP.

The control of the stepping impulse generating group and associated relays is determined by the group selecting relays G¹ and G², which are in turn controlled by the movement of a control lever effected by the dispatcher. The stepping impulse generating group of relays is composed of the master relay MR and two time spacer relays S¹ and S². Also there are the relays CL, CN and

OST which serve to control the master station selector MST step by step. The relay RE serves to accomplish the reset condition by producing a negative impulse on the transfer line, while the relay ST starts the system on its next successive cycle after the negative impulse has existed for a sufficient time to reset the system.

For purpose of simplification, the points in the circuits which are connected to common wire 200 have arrows with the reference character C. Suitable power supply, for the stepping impulses is supplied by the batteries BT¹ and BT² connected together to give positive and negative potentials respectively, in respect to the common wire 200. Other points in the circuit which are connected to a power supply, are shown as connected to indicated sources as (B) and (B-) which give positive and negative potentials with respect to said common wire 200, which in the dispatcher's office may be batteries BT¹ or BT² or other separate sources. Likewise, the indicated sources for the way stations are separate batteries at each way station, which give positive or negative potentials with respect to said common wire, and are maintained charged in any suitable manner, for example by some trickle charge method.

The dispatcher's office is connected to the way stations by four line wires, consisting of a common wire 200, a transfer wire 201, a stepping wire 202, and a message wire 203. The first way station is shown as located at the west end of a passing siding PS and is identical to the second way station located at the east end of the same passing siding PS. The relays duplicated in the several way stations have like reference characters with suitable exponents distinguishing the station to which they belong. Thus, only the first way station shown in Fig. 1B will be briefly described.

The first way station has a transfer relay TRAN¹ of the polar stick type, which controls the transfer selecting relay TS¹. These relays TRAN¹ and TS¹ compose the transfer group, determine control over the message channel selecting relays A¹, B¹ and C¹, and effect the transfer of control to the next way station. The energizing circuits of the message channel selecting relays is repeated by the line relay L¹, when the transfer line has set up communication with this particular way station.

It will be noted that the OS indication impulse is transmitted directly by the track relays to its respective OS indicating relay which in this particular embodiment of the present invention are relays OS¹ and OS², inasmuch as the system is continuously in operation. It is assumed, that where conditions would make it necessary to have OS indications stored, that a suitable means for storing OS indications may be used such as

set forth in pending application of Preston, Ser. No. 348,336, filed March 19, 1929.

Also, the lever LS has been provided to stop the system when not in use or for repairs, as the case may be. It is to be understood that should it be desired to have the system normally at rest, that means for bringing the system to rest after a certain number of cycles of operation and for again initiating the system when required, may be provided as set forth in our pending application Ser. No. 347,011, filed March 14, 1929, without departing from the present invention.

It will be stated here that all polar relays are assumed to have their contacts moved to a right hand, or positive position, with an application of positive potential to the left hand terminal of the relay, and to be moved to a left hand or negative position, with an application of negative potential to the left hand terminal thereof. It is also assumed, that the normal position of all relays is their present full line position, so that when a relay is spoken of as being in a reverse or abnormal position, it shall mean the dotted line position as shown in the accompanying drawings.

The relays MR, L⁰, L¹ and L² are of the biased-to-neutral type of polar relay. In other words their armatures move according to the polarity applied, due to the permanent magnet incorporated within the relays, but assume a neutral position when deenergized. Other polar relays are the polar permanent magnet stick type, which respond to an energy impulse for said polarity by moving its contacts to a certain position as determined by that polarity, due to a permanent magnet which is incorporated within the relay. This permanent magnet holds the armature when moved to an extreme position even though the relay is then deenergized.

The neutral relays incorporated within the circuits of the system are the usual type and are shown conventionally with heavy base lines in such cases where they have a slow releasing characteristic.

Lever SML¹ has connected to it by mechanical means the contact 11 which moves to a dotted line position when the lever SML¹ is moved to its dotted line position. Also, the lever SL¹ has connected to it by mechanical means the contacts 12 and 13, which move to their right hand dotted line positions with right hand movement of the lever SL¹, and move to a left hand dotted line position with corresponding left hand movement of the lever SL¹. Similarly the levers SML² and SL² have associated therewith corresponding contacts 14, 15 and 16 respectively.

It is believed that the system will be better understood by further description from the standpoint of operation.

Operation

Normally, the system operates to transfer

the control of the dispatcher's office from one way station to the next successive way station continuously, however for convenience in describing the operation of the present disclosure, it is deemed advisable to show the relays, control circuits and other mechanisms in the positions assumed when the system has been stopped by opening the lever LS.

It will be noted, that the operation of this system, namely, the transfer from station to station is accomplished by successive positive transfer impulses and the system is re-set or sectionalized by a negative impulse. The system is so organized that when the lever LS is moved to a downward position to stop the system, that the system will always operate up to the positions assumed during the time that the re-set negative impulse is placed on the transfer wire 201, which in this specific embodiment leaves the relays CN, RE, TS¹ and TS² in energized positions.

The relay CN is energized through a circuit traced as follows:—from positive terminal of indicated source having suitable potential, through front contact 7, wire 15, relay CN, to the common wire 200.

The energizing circuit for the relay RE is traced as follows:—from positive terminal of indicated source having suitable potential, through relay RE, wire 16, reset contact 22 of circuit selector S, through arm 17 to the common wire 200.

The relays TS¹ and TS² are held energized through similar symmetrical circuits, with the circuit for relay TS¹ traced as follows:—from the positive terminal of indicated source having suitable potential, through negative contact 18 of relay TRAN¹, wire 19, upper winding of relay TS¹, to the common wire 200.

OS indication scanning.—When the lever LS is moved to an upward extreme position to cut in the system, the system operates through a time cycle including the scanning of all OS indications, so that the indicator light I¹ for station one and representing track section TK¹, indicates the occupancy or un-occupancy of said track section TK¹, likewise indicator lamp I² associated with track section TK² and all other indicator lamps representing other OS-ing track sections are caused to give proper indications. This operation which may be called OS scanning, reduces the time cycle of the system to a minimum value for transmitting said OS indication impulses to the dispatcher's office as quickly as possible, and without reducing the facility with which the system can transmit control indication impulses.

Assuming that the lever LS is moved to the upward extreme position, energy is applied to the electro-magnet E causing the ratchet R to retract one step on the sprocket SP thus opening the front contacts 7 and 8. The opening of front contact 7 opens the en-

ergizing circuit for the relay CN, which in turn opens the energizing circuit of the electro-magnet E and relay OST. The deenergization of electro-magnet E, allows the armature A, lever L and ratchet R to return to their biased positions so that the sprocket SP rotates the shaft of the master station selector MST one step, so that the arms 17, 20 and 21 of the circuit selectors S, T and M respectively move to the "1st" step positions. The returning of the contacts 7 and 8 to their biased positions close the energizing circuit for the relay CN, and also the movement of arm 17 of circuit selector S moving to the "1st" step position, opens the circuit for the re-set relay RE, so that the relay CN becomes energized at the same time that the relay RE becomes deenergized. Thus a positive impulse is placed upon the transfer wire 201, which energizes the polar contacts of relay TRAN¹ at the first way station to a positive position deenergizing the upper coil of relay TS¹. However, as long as the positive transfer impulse exists the relay TS¹ is still held energized through a stick circuit including its lower winding and a front contact. At this time a circuit is completed for transmitting the OS indication impulse from the track relay TR¹ to the OS indicating relay OS¹. However, the system does not remain selected for the first way station, due to the fact that as soon as the relay CN becomes energized, the circuit for energizing the electro-magnet E is again completed providing that there has been no lever movement by the dispatcher. It is of course to be understood that the time consumed by the energization of the electro-magnet E and the attraction of the armature A is sufficient to allow the transmission of the OS indication impulse before the positive transfer impulse is broken at the front contact 8.

It is now easily seen that as soon as the front contact 7 is open the relay CN is again deenergized, the circuit for the electro-magnet E is broken and the arms 17, 20 and 21 of the circuit selectors S, T and M respectively are moved to the "2nd" step positions, thus selecting the second way station as soon as the relay CN again reaches its energized position. Similarly, the other stations of the system are selected successively.

More specifically, the upward movement of lever LS closes the contact 23 for completing the circuit for the electro-magnet E and the relay OST, which is traced as follows:—from positive terminal of indicated source having suitable potential, through back contact 24 of relay ST, wire 25, contact 23, wire 26, starting contact 27 of circuit selector T, arm 20, wire 28, electro-magnet E, wire 29, relay OST, wire 30, front contact 31 of relay CN, to the common wire 200.

It will be noted here that the relay OST is a slow releasing relay having such charac-

teristics in order that it does not drop away during the interval between transfer impulses of the normal rate. In other words, the normal rate of the transfer impulses supplies sufficient energy to maintain contact of the relay OST in the attracted energized position, while if the energizing circuit for relay OST is opened for a time greater than twice the normal interval between transfer impulses, then its contacts assume a deenergized position.

Also, the closing of front contact 23^a of lever LS, closes a circuit through back contact 32 of relay OST for permitting the stepping impulse relay group composed of relays MR, S¹ and S² to operate. However, the contact 32 of relay OST is immediately moved to an energized position simultaneously with the energization of electro-magnet E, so that the stepping impulse relay group does not have time to operate for producing more than possibly two or three stepping impulses. This is not objectionable because it occurs only at such time that the system is started after being under repairs or in disuse. Also, the stepping impulses can accomplish no harm, as the circuit selectors of the master station selector MST are at the reset positions.

At this time the electro-magnet E is energized, the armature A is in an attracted position, resulting in the opening of contacts 7 and 8. The energizing circuit of the relay CN is now open at contact 7.

The deenergization of relay CN opens the energizing circuit of the electro-magnet E and the relay OST at the front contact 31 of the relay CN. The armature A is now released, and the contacts 7 and 8 assume their biased closed positions. Also, the circuit selectors M, S and T have moved to the first step position.

With the circuit selectors M, S and T in the "1st" step position, the energizing circuit for the relay RE is broken at the reset contact 22 of the circuit selector S. The relay CN is now energized with the contact 7 in its biased position. Thus it is seen that the relay RE becomes deenergized at the same time that the relay CN becomes energized, which completes a circuit for placing positive potential upon the transfer wire 201, which is traced as follows:—from positive terminal of indicated source having suitable potential, through front contact 33 of relay CN, to wire 34, front contact 8, wire 35, back contact 36 of relay RE, to the transfer wire 201 to the first way station, wire 37, relay TRAN¹, wire 38 and 39, lower winding of relay TS¹, wire 40, front contact 41 of relay TS¹, to the common wire 200. Thus, the polar contacts of relay TRAN¹ will move to a positive position, energizing the upper winding of relay TS¹. In this connection, attention is directed to the fact that the deenergization of magnet E re-

sulting in the movement of arms 21, 17 and 20 of circuit selectors M, S and T respectively, from their zero reset position causes the first application of positive potential to the transfer wire 201, so that the first way station (see Fig. 1B) is selected while the arm 21 assumes the position "1st".

The deenergization of relay RE closes a circuit through back contact 36^a for energizing relay ST, as is obvious from the drawing, which has no effect on the operation of the system until during the last step of the cycle, namely the zero reset position. The positive impulse for energizing the polar contacts of relay TRAN¹ to a positive position and holding the neutral contacts of the relay TS¹ in an energized position, continues until the armature A is attracted by the electro-magnet E, due to the electro-magnet E being energized through a circuit traced as follows:—

from positive terminal of indicated source having suitable potential, through back contact 42 of relay G¹, wire 43 and 44, first contact of circuit selector T, arm 20, wire 28, electro-magnet E, wire 29, relay OST, wire 30, front contact 31 of relay CN, to the common wire 200.

At this time the front contact 8 is open discontinuing the positive impulse which holds the relay TS¹ energized, thereby effecting dropping of contacts of relay TS¹ and connecting the transfer line 201 to the second way station through back contact 45 of relay TS¹. Also the energizing circuit of relay CN is opened at front contact 7, so that during the time that the contacts of relay TS¹ at the first way station are assuming a deenergized position, the contacts of the relay CN are also assuming a deenergized position.

As soon as the contacts 45 and 46 of the relay TS¹ assume their deenergized positions the transfer wire 201 and the stepping wire 202 are made continuous to the second way station. The contacts of relay TS¹ have plenty of time to assume deenergized positions while the relay CN becomes deenergized resulting in the deenergization of the electro-magnet E and producing the movement of the circuit selectors M, S and T to their second step positions engaging contacts "2nd." During the time that the circuit selectors M, S and T are in the "1st" step positions and the relays CN, TRAN¹ and TS¹ are energized with the positive transfer impulse, a message channel is set up for the transmission of the OS indication at the first way station. Inasmuch as the track section TK¹ is unoccupied, the track relay TR¹ is energized, so that a negative impulse will be placed upon the relay OS^a through the OS indication message channel for the first way station, which is traced as follows:—

from negative terminal of indicated source having suitable potential, through front contact 47 of relay TR¹, wire 48, back contact 49 of re-

lay A¹, wire 50, back contact 51 of relay B¹, wire 52, back contact 53 of relay C¹, wire 54, front contact 55 of relay TS¹, wire 56, positive contact 57 of relay TRAN¹, wire 58, message wire 203 to the dispatchers' office, 70 arm 21 of the circuit selector M, "1st" step contact of circuit selector M, wire 59, back contact 60 of relay 3¹, wire 61, back contact 62 of relay 2¹, wire 63, back contact 64 of relay 1¹, wire 65, relay OS¹, to the common 75 wire 200. This negative impulse upon the relay OS¹ results in its polar contact remaining in its present negative position. Thus the indicator lamp 1¹ remains unilluminated indicating to the dispatcher that the track section 80 TK¹ is still unoccupied.

With the electro-magnet E deenergized and the circuit selectors M, S and T in the "2nd" step positions, the contact 7 is closed completing the energizing circuit for relay 85 CN, also the front contact 8 completes a circuit for placing positive potential upon the transfer wire 201 which results in the selection of the second way station.

The positive impulse for selecting the second way station passes through a circuit traced as follows:—

from positive terminal of indicated source having suitable potential, through front contact 33 of relay CN, wire 34, front contact 8, wire 35, back contact 36 of the 90 relay RE, transfer wire 201 to the first way station, wire 66, back contact 45 of the relay TS¹ to the second way station over a transfer wire 201, wire 67, transfer relay TRAN², wire 68 and 69, lower winding of relay TS², 100 wire 70, front contact 71 of relay TS², to the common wire 200.

Thus the polar contacts of relay TRAN² are moved to a positive position, and the neutral contacts of relay TS² are held in an energized position by this same positive transfer impulse.

At this time a message channel is set up for transmitting the OS indication of the second way station to the dispatcher's office. As the track section TK² is unoccupied, a negative impulse will be applied to the relay OS² in the dispatcher's office through this message channel which is traced as follows:—

from negative terminal of indicated source having suitable potential, through front contact 72 of relay TR², wire 73, back contact 74 of relay A², wire 75, back contact 76 of relay B², wire 77, back contact 78 of relay C², wire 79, front contact 80 of relay T², wire 81, positive contact 82 of relay TRAN², wire 83, message wire 203 to the dispatcher's office, arm 21 of circuit selector M, contact "2nd" of circuit selector M, wire 84, back contact 85 of relay 3², wire 86, back contact 87 of relay 2², wire 88, back contact 89 of relay 1², wire 90, relay OS², to the common wire 200. Thus, the polar contact of relay OS² remains in a negative position resulting in the indicator lamp I² remaining unilluminated, which indicates to 130

the dispatcher that the track section TK^3 is still unoccupied.

Thus, the system continues to operate step by step, or in other words, transfers the control of the dispatcher's office from one way station to the next way station in a manner identical to that heretofore described. At each way station the OS indications are transmitted to the dispatcher's office immediately notifying the dispatcher of any change in track conditions or more specifically indicating the progress of trains by indicating the presence of a train on a particular track section by the illumination of its respective indicator lamp upon the dispatcher's panel. It is easily seen that should either the track section TK^1 or the track section TK^3 be occupied, that the respective track relays TR^1 or TR^2 would be deenergized transmitting to the respective OS indicating relays positive impulses instead of negative impulses, which would result in the illumination of the respective indicator lamp I^1 or I^3 , due to the polar contacts of the relays OS^1 and OS^2 respectively being in a positive position energizing its respective indicator lamp over a circuit which is obvious from the drawing.

The system now operates, until the next to the last step is reached by the circuit selector M, S and T, at which time the relay CL is energized over a circuit traced as follows:—from positive terminal of indicated source having suitable potential, through relay CL, wire 91, contact 92 of the circuit selector S, contact arm 17, to the common wire 200. Thus, the relay CL is energized, and at the same time indicator lamp I^0 is illuminated over the same circuit which is apparent from the drawing.

The circuit selectors take the next step bringing them to the reset position, at which time the relay RE is energized through a circuit heretofore traced. It should be remembered that the stationary contact 27 of selector T is now deenergized so that the stepping action of the magnet E is discontinued for the time being at least. The energization of relay RE results in the deenergization of relay ST, which drops its neutral contact through a slow releasing period of sufficient extent to allow the negative impulse, which is placed upon the transfer wire, to reset or sectionalize the transfer line 201. This negative impulse is placed upon the transfer wire 201 in a manner that is obvious from the drawing at the time that the relay RE is energized, and moves the polar contacts of all of the transfer relays $TRAN^1$ and $TRAN^2$ to a negative position before any of their respective relays TS^1 and TS^2 reach their energized positions, due to their energizing circuit being completed by the polar contacts of said transfer relays, this being true because the relays TS^1 , TS^2 , etc., are slower acting than the relays $TRAN^1$, $TRAN^2$, etc.

As soon as the relay ST becomes fully deenergized the back contact 24 completes the circuit for energizing the electro-magnet E and the system again operates through another cycle for scanning the OS indications. 70

Transmission of control indications.—The transmission of a control indication impulse does not effect the scanning of OS indication in any manner except after the OS indication for the particular way station, which is to receive a control indication has been transmitted, a pause in transfer occurs, at which time the relay OST becomes deenergized allowing the stepping impulse group 80 of relays comprising relays MR, S^1 and S^2 to operate. The function of these relays is to operate the message channel selecting relays in the dispatcher's office representing that particular way station and the message channel selecting relays at that way station, until these message channel selecting relays have successively completed all the control indication message channels for that way station, after which the system transfers the control 90 to the next way station and continues scanning the OS indications, until some other station is selected to which a control indication is to be transmitted. 85

As the back contact 93 of relay CL closes the stick circuit for the group selecting relays G^1 and G^2 , the control levers must be moved at such time that this stick circuit is closed, so that their respective group relay will remain energized during a complete total time 100 cycle. It will also be seen, that it is necessary for a lever to be thrown immediately upon the closing of this stick circuit, so that the transmission of the control indication impulse is insured during that cycle. If the lever was 105 thrown during the second half of the cycle and the message channel over which the control indication impulse should have been transmitted occurred during the first half of the cycle, then the group selecting relay would 110 become deenergized at the end of the cycle and the control indication impulse would not be transmitted. The indicator I^0 is illuminated at the time that the stick circuit for relays G^1 and G^2 is opened, so that if a lever 115 is moved immediately after the momentary illumination of said indicator I^0 the stick circuit will be closed, and the control indication impulse will be insured of transmission. 120

By way of illustration, let us assume that the dispatcher desires to reverse the switch machine at the east end of the passing siding PS to allow traffic to be routed into the passing siding. To do this he moves the lever SML^2 to the right hand dotted position and in so doing the contact 14 associated with lever SML^2 passes over its momentarily made contact so that the relay G^2 is energized through a circuit traced as follows:—from positive terminal of indicated source having 125

suitable potential, through relay G^2 , wire 94, wire 95 and 96, momentarily made contact 14, to the common wire 200. The relay G^2 is now held energized through a stick circuit traced as follows:—from positive terminal of indicated source having suitable potential, through relay G^2 , wires 94 and 97, front contact 98, wires 99 and 100, back contact 93 of relay CL to the common wire 200. The relay G^2 is thus held energized until the relay CL is energized and opens the back contact 93 which occurs at the end of each cycle.

As the lever SML² was moved immediately after the illumination of the indicator lamp I^0 , a time interval equal to the reset period occurred before the circuit selectors M, S and T move to the "1st" step position. It is assumed, that the master selector MST steps along until the "2nd" step position is reached, at which time the electro-magnet E cannot receive energy due to the energization of the relay G^2 opening the circuit of electro-magnet E at the back contact 101 of the relay G^2 . When this time interval, after the last energization of electro-magnet E and relay OST, has continued for a time equal to twice the normal time interval between transfer impulses, then the contact 32 of relay OST becomes fully deenergized completing a circuit for allowing the stepping impulse relay group MR, S^1 , S^2 to operate for placing stepping impulses upon the stepping wire 202.

If the first impulse produced by the stepping impulse relay group composed of relays MR, S^1 and S^2 should be a negative impulse it would be ineffective to produce the energization of any message channel selecting relay. Hence, we will assume that the stepping impulse generating group of relays are in their present full line positions, so that when the back contact 32 is closed, that a circuit is set up for energizing the master relay MR to a positive position.

For the purpose of simplicity only the circuits will be traced for the operation of the stepping impulse relay group as its operation and function is fully described in pending application of Hitchcock and Dicke, Ser. No. 345,637, filed March 9, 1929. This application also describes how the message wire may be connected through the contacts of the stepping impulse group so that the messages will be sent over their message channels only during a central interval of time of the total channel time. It is to be understood that the same principle may be applied to this specific embodiment without departing from the scope of the present invention. Also the message channel selecting group of relays, such as relays 1^2 , 2^2 and 3^2 have their operation and function fully described in pending application of O. H. Dicke, Ser. No. 354,881, filed April 13, 1929, so that it is only necessary to trace the circuits involved in the present invention.

With the back contact 32 of relay OST fully deenergized, positive energy is placed upon the master relay MR through a circuit traced as follows:—from the positive terminal of battery BT¹, through wires 102 and 103, positive contact 104 of relay S^2 , wire 105, back contact 32 of relay OST, wire 106, front contact 23^a of lever LS, wire 107, master relay MR, wire 108 and 109 to the common wire 200. The contact 110 of the master relay MR is energized to a positive position placing positive potential upon the stepping line operating the contacts of line relays L^0 and L^2 to positive positions which in turn energized the relays 1^2 and A^2 . This positive impulse is placed upon the stepping line through a circuit traced as follows:—from the positive terminal of battery BT¹, to wires 111, positive contact 110, wire 112, relay S^1 , wire 113, relay L^0 , through the stepping wire 202 to the first way station, through back contact 46 of relay TS¹, through the stepping wire 202, to the second way station, through front contact 114 of relay TS², wire 115, relay L^2 , to the common wire 200. Thus the contact 116 of relay S^1 , contact 117 of relay L^0 and the contact 118 of the relay L^2 are moved to positive positions.

With the positive contact 117 of relay L^0 closed a circuit is completed for energizing the relay 1^2 , which is traced as follows:—from positive terminal of indicated source having suitable potential, through positive contact 117 of relay L^0 , wires 119 and 120, back contact 121 of relay 2^2 , wires 122 and 123, relay 1^2 , wire 124, back contact 125 of relay 2^2 , wire 126 and 127, back contact 128 of relay 3^2 , wires 129 and 130, second contact of circuit selector S, arm 17, to the common wire 200. The energization of relay 1^2 closes a stick circuit through front contact 131 as is obvious from the drawing.

At the second way station the relay A^2 is energized through similar symmetrical circuits as relay 1^2 , due to the fact that the contact 118 of relay L^2 is in a positive position. Upon the energization of relays 1^2 or A^2 a message channel is completed for energizing the relay SMR² which in turn controls the switch machine SM² for reversing track switch TS².

This message channel for controlling the switch machine relay SMR² for controlling the track switch TS² is traced as follows:—from positive terminal of indicated source having suitable potential, through lever SML² in a right hand position, through wire 132, front contact 89 of relay 1^2 , wire 88, back contact 87 of relay 2^2 , wire 86, back contact 85 of relay 3^2 , wire 84, "2nd" step contact of circuit selector M, arm 21, through the message wire 203 to the second way station, wire 83, positive contact 82 of relay TRAN², wire 81, front contact 80 of relay TS², wire 79.

back contact 78 of relay C², wire 77, back contact 76 of relay B², wire 75, front contact 74 of relay A², wire 133, relay SMR² to the common wire 200. The polar contact of relay 5 SMR² is thus moved to a negative position controlling the track switch TS² to a reverse position routing traffic upon the passing siding PS, when the signal SW⁴ has been cleared.

With the polar contact 116 of relay S¹ in 10 a positive position the contact 104 of relay S² is energized to a negative position through a circuit traced as follows:—from the negative terminal of battery BT², through wires 134 and 135, positive contact 116 of relay S¹, wire 15 136, relay S², wire 137 and 109 to the common wire 200. Thus the polar contact 104 of relay S² is moved to a negative position placing a negative potential upon the relay MR, through a circuit traced as follows:—from 20 the negative terminal of battery BT², wires 134 and 138, negative contact 104 of relay S², wires 105, back contact 32 of relay OST, wire 106, front contact 23^a of lever LS, wire 107, relay MR, wire 108 and 109, to the common 25 wire 200. Thus, the contact 110 of the relay MR is energized to a negative position placing negative potential upon the relays S¹, L⁰ and L² from the negative terminal of battery BT² through wire 139, negative contact 30 110, through a circuit heretofore traced for energizing the relays S¹, L⁰ and L². The contact 116 of relay S¹ is moved to a negative position, thus causing the contact 104 of relay S² to be moved to a positive position, resulting in the energization of the master 35 relay MR with a positive impulse which occurs in due time.

In the mean time with the contacts of the line relays in a negative position the relays 40 2² and B² are energized and the stick circuits of the relays 1² and A² are opened by back contacts of relays 2² and B².

The relay 2² is energized through a circuit traced as follows:—from positive terminal of 45 indicated source having suitable potential negative contact 117 of relay L⁰, wire 140 and 141, front contact 142, wires 143 and 144, relay 2², wires 145 and 127, back contact 128, wires 129 and 130, “2nd” step contact of circuit selector S, arm 17, to the common wire 200. The relay B² is energized with contact 50 118 of relay L² in a negative position through a similar circuit. The relay 2² is held energized through a stick circuit including front contact 146.

The next impulse placed upon the stepping line by the stepping impulse generating relay group is a positive one and energizes the contacts of relays S¹, L⁰ and L² to a positive position. With the contact 117 of relay L⁰ in a positive position the relay 2² is energized through a circuit traced as follows:—from positive terminal of indicated source having suitable potential, positive contact 117 of relay L⁰, wire 119 and 120, front contact 121,

wire 147 and 148, relay 3², wires 149 and 130, of the “2nd” step contact of selector S, arm 17 to the common wire 200. The relay 3² is held energized through a stick circuit including front contact 150 until the stick circuit is open by the movement of selector arm 17 to the “3rd” step position. The relay C² is energized through similar circuits simultaneously with relay 3².

Upon the energization of relay 3² a circuit 70 is completed for energizing the electro magnet E and relay OST, which is traced as follows:—from the positive terminal of indicated source having suitable potential through front contact 151 of relay 3², wire 152 and 153, “2nd” step contact of circuit selector T, arm 20, wire 28, electro-magnet E, wire 29, relay OST, wire 30, front contact 31 of relay CN, to the common wire 200. The electro-magnet E and relay OST are thus 80 energized. The stepping impulses are thus discontinued by the attraction of back contact 32 of relay OST. Also, the circuit selectors M, S and T are moved to the “3rd” step position as soon as the relay CN becomes de-energized allowing the armature A to be released. The stick circuit for the relay 3² is now opened at the “2nd” step contact of circuit selector S, also the third way station has 90 been selected, so that the relay TS² of the second way station has been deenergized and the stick circuit of the relay C² has been opened at the front contact 151 of the relay TS².

The master circuit selector MST proceeds 100 to select further way station as herebefore described. At the next to the last step the relay CL is energized and the stick circuit for the relay G² is opened at the back contact 95 93. A description of the transmission of a control indication impulse has thus been given and in a similar manner all other control impulses are transmitted according to the movement of any particular control lever.

It is noted that the regular OS-scanning 110 is interrupted for the transmission of a control impulse only at the time that the station is selected to which the control impulse is to be transmitted. Thus, the total time cycle of the system is not materially increased by the transmission of a comparatively large number of control indication impulses.

The manner in which the system is organized in order to accomplish automatic hesitation at a particular way station for the transmission of control impulses has thus been shown. This hesitation at a particular way station is accomplished by the energization of the group selecting relay, such as relay G² representing that station which is effected by the movement of any control lever which is used for transmitting control indication impulses to that particular way station.

In order for the dispatcher to clear the signal SW⁴ with the switch machine SM² in a 130

reverse position, the lever SL^2 must be moved to a left hand position, which causes a negative impulse to be placed upon the direction relay DR^2 and a positive impulse on the signal relay SR^2 over their respective message channels. The manner in which the signals are controlled in accordance with the position of the switch machine SM^2 and the relays DR^2 and SR^2 is completely set forth in the application by S. N. Wight, Ser. No. 321,185, filed November 22, 1928. Similarly, the movement of lever SML^1 to a right hand position reverses the track switch TS^1 by sending a negative impulse to the relay SMR^1 over its respective message channel. Also lever SL^1 moved to a left hand position, transmits a negative impulse to the direction relay DR^1 and a positive impulse to the signal relay SR^1 over their respective message channels. It must be remembered that in every case where a lever movement is made that it must be done immediately after the illumination of indicator lamp I^0 , so that the stick circuit for the group selecting relay representing that particular station may be completed. In this connection, if desired the group selecting relay, such as G^2 , may be stuck up for two cycles of operation in a manner taught in the application of Hitchcock and Dicke, Ser. No. 345,667 above referred to.

Assuming that the levers SL^2 , SML^1 and SL^1 have been moved to left hand positions so that a train may be routed over the passing siding, the message channels for the respective control relays will be traced. It will also be assumed that the system steps along in a manner as heretofore described and hesitates at their respective steps and at proper times as heretofore described.

40 The message channel for the relay DR^2 is traced as follows:—from negative terminal of indicated source having suitable potential, through lever SL^2 in a left hand position, wire 152, front contact 87 of relay 2^2 , wire 45 86, back contact 85, of relay 3^2 , wire 84, second step contact of selector M , arm 21, through the message wire 203 to the second way station, wire 83, positive contact 82 of relay $TRAN^2$, wire 81, front contact 80 of relay TS^2 , wire 79, back contact 78 of relay C^2 , wire 77, front contact 76 of relay B^2 , wire 153, relay DR^2 , to the common wire 200.

The message channel for the signal relay SR^2 is traced as follows:—from positive terminal of indicated source having suitable potential, through contact 15 in a left hand position, wire 154, front contact 85 of relay 3^2 , wire 84, second step contact of circuit selector M , arm 21 through the message wire 203 to the second way station, wire 83, positive contact 82 of relay $TRAN^2$, wire 81, front contact 80 of relay TS^2 , wire 79, front contact 78 of relay C^2 , wire 155, relay SR^2 , to the common wire 200.

65 The message channel for the switch ma-

chine relay SMR^1 is traced as follows:—from negative terminal of indicated source having suitable potential, through lever SML^1 in a right hand position, wire 156, front contact 64 of relay 1^1 , wire 63, back contact 62 of relay 2^1 , wire 61, back contact 60 of relay 3^1 , wire 59, first step contact of circuit selector M , arm 21, through the message wire 203, to the first way station, wire 58, positive contact 57 of relay $TRAN^1$, wire 56, front contact 55 of relay TS^1 , wire 54, back contact 53 of relay C^1 , wire 52, back contact 51 of relay B^1 , wire 50, front contact 49 of relay A^1 , wire 157, relay SMR^1 , to the common wire 200.

The message channel for the relay DR^1 is traced as follows:—from negative terminal of indicated source having suitable potential, through lever SL^1 in the left hand position, wire 158, front contact 62 of relay 2^1 , wire 61, back contact 60 of relay 3^1 , wire 59, first step contact of circuit selector M , arm 21, through the message wire 203 to the first way station, wire 58, positive contact 57 of relay $TRAN^1$, wire 56, front contact 55 of relay TS^1 , wire 54, back contact 53 of relay C^1 , wire 52, front contact 51 of relay B^1 , wire 159 of relay DR^1 , to the common wire 200.

The message channel for the relay SR^1 is traced as follows:—from the positive terminal of indicated source having suitable potential, through contact 12 in a left hand position, wire 160, front contact 60 of relay 3^1 , wire 59, first step contact of circuit selector M , arm 21, through the message wire 203 to the first way station, wire 58, positive contact 57 of relay $TRAN^1$, wire 56, front contact 55 of relay TS^1 , wire 54, front contact 53 of relay C^1 , wire 161, relay SR^1 , to the common wire 200.

Summary

105

It is noted that the total time cycle of the system embodying the present invention is variable from a minimum value, including the scanning of all OS indications, to a maximum value including the scanning of all OS indications plus the transmission of all control indication impulses. However, as the number of control indication impulses are comparatively few for any one total time cycle, then the total time cycle is usually of a value near the minimum.

The automatic picking of OS indications during the transfer operation from station to station, is peculiarly adaptable to dispatching systems where there is but one OS indication to be picked up at each way station and where there are several traffic controlling devices at that way station to be controlled. Also, this specific embodiment inherently causes the isolation of all message channels so that any short circuit or defect at a particular message channel does not effect message channels of other way stations. Another advantageous feature of the present

110

115

120

125

130

invention is involved in the complete synchronization of the whole system at the end of each total time cycle.

Having thus shown and described one specific embodiment of a rather involved and comprehensive system for carrying out certain functions, it is desired to be understood that the particular arrangement of devices and circuits illustrated, need not be adhered to, but that many changes, modifications and additions may be made, in the individual device as well as in their coordination with each other, without departing from the scope or spirit of the invention, except as demanded by the scope of the appended claims.

What we claim is:—

1. In a train dispatching system of the synchronous selector wayside signal control type, the combination with a dispatcher's office and a plurality of way stations along the railway track, of a master synchronous selector at the dispatcher's office, a wayside synchronous selector distributed along the railway track, stepping means for operating said synchronous selectors in synchronism to successively complete a large number of message circuits, there being only one OS-ing message circuit and at least one control message circuit for each way station, said stepping means including means for at times setting up successively said OS-ing message circuit only and at other times setting up said OS-ing message circuits and said control message circuits sequentially.

2. In a train dispatching system of the synchronous selector wayside signal control type, the combination with a dispatcher's office and a plurality of way stations along the railway track, of a master synchronous selector at the dispatcher's office, a wayside synchronous selector distributed along the railway track, stepping means for operating said synchronous selectors in synchronism to successively complete a large number of message circuits, there being only one OS-ing message circuit and at least one control message circuit for each way station, said stepping means including means for at times setting up successively said OS-ing message circuit only and at other times setting up said OS-ing message circuits and said control message circuits sequentially.

3. In a train dispatching system of the synchronous selector wayside signal control type, the combination with a dispatcher's office and a plurality of way stations along the railway track, of a master synchronous selector at the dispatcher's office, a wayside synchronous selector distributed along the railway track, stepping means for operating said synchronous selectors in synchronism to successively complete a large number of message circuits, there being only one OS-ing message circuit and at least one control message circuit for each way station, said step-

ping means including means for at times hurdling some of said control circuits but not hurdling any of said OS-ing message circuits.

4. A synchronous selector train dispatching system comprising, a combined way station selecting and OS message circuit closing synchronous selector located at the dispatcher's office, a similar combined way station selector and OS message circuit closing synchronous selector distributed along the track with portions thereof at each of a plurality of way stations, supplemental home synchronous selectors one for each way station at the dispatcher's office, a supplemental way station synchronous selector at each way station, means for operating the two mentioned way station selecting and OS message circuit closing synchronous selectors in synchronism to successively select all of said OS message circuits and including means for at times hesitating when a particular way station is selected and effecting the operation of the supplemental synchronous selectors for such particular way station to close a particular control message circuit, and wayside signals controlled over said control message circuits.

5. A synchronous selector train dispatching system comprising, a combined way station selecting and OS message circuit closing synchronous selector located at the dispatcher's office, a similar combined way station selector and OS message circuit closing synchronous selector distributed along the track with portions thereof at each of a plurality of way stations, supplemental home synchronous selectors one for each way station at the dispatcher's office, a supplemental way station synchronous selector at each way station, means for operating the two mentioned way station selecting and OS message circuit closing synchronous selectors in synchronism to successively select all of said OS message circuits and including means for at times hesitating when a particular way station is selected and effecting the operation of the supplemental synchronous selectors for such particular way station to close successively all of the control message circuits at such way station, and wayside signals controlled over said control message circuits.

6. In a train dispatching system of the synchronous selector type; the combination with a dispatcher's office and a plurality of way stations along the railway track; of a home synchronous selector comprising, a rotary shaft having a plurality of contact arms for engaging stationary contacts and connected to a ratchet wheel, a spring operated pawl for operating said ratchet wheel one step at a time, an electromagnet for retracting said pawl and reloading said spring, a circuit for each step of operation for said electro-magnet including contacts closed only in the last preceding step of said home selec-

tor, means for opening such circuit when said electro-magnet has been completely retracted, whereby said home selector is operated step by step until it reaches a position where the circuit for said electro-magnet is not reclosed; a way station synchronous selector including a plurality of sequentially operated relays operated step by step in synchronism with said home synchronous selector; a plurality of message circuits including contacts of said home selector and contacts of said way station selector, and wayside signals controlled over said message circuits.

7. In a train dispatching system of the synchronous selector type; the combination with a dispatcher's office and a plurality of way stations along the railway track; of a home synchronous selector comprising, a rotary shaft having a plurality of contact arms for engaging stationary contacts and connected to a ratchet wheel, a spring operated pawl for operating said ratchet wheel one step at a time, an electro-magnet for retracting said pawl and reloading said spring, a circuit for each step of operation for said electro-magnet including contacts closed only in the last preceding step of said home selector, means for opening such circuit when said electro-magnet has been completely retracted, whereby said home selector is operated step by step until it reaches a position where the circuit for said electro-magnet is not reclosed; a way station synchronous selector including a plurality of sequentially operated relays operated step by step in synchronism with said home synchronous selector; a plurality of message circuits including contacts of said home selector and said way station selector, wayside signals controlled over said message circuits, supplemental synchronous selectors so that said home synchronous selector is held at rest until the contact of said supplemental synchronous selector is closed.

8. In a train dispatching system of the synchronous selector type, the combination with a dispatcher's office and a plurality of way stations along the railway track; of a home synchronous selector comprising, a rotary shaft having a plurality of contact arms for engaging stationary contacts and connected to a ratchet wheel, a spring operated pawl for operating said ratchet wheel one step at a time, an electro-magnet for retracting said pawl and reloading said spring, a circuit for each step of operation for said electro-magnet including contacts closed only in the last preceding step of said home selector, means for opening such circuit when said electro-magnet has been completely retracted, whereby said home selector is operated step by step until it reaches a position where the circuit for said electro-magnet is

not reclosed; a way station synchronous selector including a plurality of sequentially operated relays operated step by step in synchronism with said home synchronous selector; a plurality of message circuits including contacts of said home selector and contacts of said way station selector, wayside signals controlled over said message circuits, supplemental synchronous selector operable over the same line circuits, and means for at times carrying the circuit for said electro-magnet through a contact of one of said supplemental synchronous selectors so that said home synchronous selector is held at rest until the contact of said supplemental synchronous selector is closed. 70

9. In a train dispatching system of the synchronous selector type; the combination with a dispatcher's office and a plurality of way stations along the railway track; of a home synchronous selector comprising, a rotary shaft having a contact arm for engaging stationary contacts and connected to a ratchet wheel, a spring operated pawl for operating said ratchet wheel one step at a time, an electro-magnet for retracting said pawl and reloading said spring, a circuit for each step of operation for said electro-magnet including contacts closed only in the last preceding step of said home selector, means for opening such circuit when said electro-magnet has been completely retracted, whereby said home selector is operated step by step until it reaches a position where the circuit for said selector is not reclosed; another synchronous selector operated in synchronism with said home synchronous selector selecting a different way station for each step of said home synchronous selector, a supplemental synchronous selector at said dispatcher's office and at each of said way stations, and means for causing said home and said another synchronous selectors to hesitate when a particular way station is selected for permitting the corresponding supplemental synchronous selector to complete its operating cycle. 95

10. In a train dispatching system of the synchronous selector type; the combination with a dispatcher's office and a plurality of way stations along the railway track; of a home synchronous selector comprising, a rotary shaft having a contact arm for engaging stationary contacts and connected to a ratchet wheel, a spring operated pawl for operating said ratchet wheel one step at a time, an electro-magnet for retracting said pawl and reloading said spring, a circuit for each step of operation for said electro-magnet including contacts closed only in the last preceding step of said home selector, means for opening such circuit when said electro-magnet has been entirely retracted, whereby said home selector is operated step by step until it reaches a position where the circuit 110

- for said electro-magnet is not reclosed; a stick relay, a lever controlling a distant traffic controlling device through the medium of said home synchronous selector, a pick-up circuit 5 for said stick relay closed momentarily upon movement of said lever from one to another of its operated positions, a stick circuit for said relay broken momentarily when the synchronous selector has completed a particular 10 operating cycle, a back contact on said stick relay included in the energizing circuit for said electro-magnet when said home synchronous selector assumes a particular step, thereby causing said home synchronous selector to 15 stop when it reaches that particular step; a supplemental synchronous selector initiated if the home synchronous selector hesitates at that particular step for more than a predetermined period of time; and a contact connected in multiple with said back contact and closed only when said supplemental synchronous selector has been operated.
11. In a train dispatching system of the synchronous selector type; the combination with a dispatcher's office and a plurality of way stations along the railway track; of a home synchronous selector comprising, a rotary shaft having a contact arm for engaging stationary contacts and connected to a 20 ratchet wheel, a spring operated pawl for operating said ratchet wheel one step at a time, an electro-magnet for retracting said pawl and reloading said spring, a circuit for each step of operation of said selector 25 for said electro-magnet including contacts closed only in the last preceding step of said home selector, means for opening such circuit when said electro-magnet has been completely retracted, whereby said home selector 30 is operated step by step until it reaches a position where the circuit for said electro-magnet is not reclosed; a stick relay, a lever controlling a distant traffic controlling device through the medium of said home synchronous selector, a pick-up circuit for said 35 stick relay closed momentarily upon movement of said lever from one to another of its operated positions, a stick circuit for said stick relay broken momentarily when the 40 synchronous selector has completed a particular operating cycle, a back contact on said relay included in the energizing circuit for said electro-magnet when said home synchronous selector assumes a particular step, 45 thereby causing said home synchronous selector to stop when it reaches that particular step; a supplemental synchronous selector initiated if the home synchronous selector hesitates at that particular step for 50 more than a predetermined period of time; and a contact connected in multiple with said back contact and closed only when said supplemental synchronous selector has completed its cycle of operation.
- 55 12. A method of train dispatching includ-

ing the control of switch machines and signals from a dispatcher's office and the indication of distant track circuit occupancy in said dispatcher's office through the medium of synchronous selectors, which consists in normally scanning all indicating message circuits sequentially in rapid succession of a synchronous selector system; and in at other times hesitating at a particular indicating message circuit and during such hesitation scanning a plurality of control message circuits in rapid succession.

13. A method of train dispatching including the control of switch machines and signals from a dispatcher's office and the indication in the dispatcher's office of track circuit occupancy of distant track circuits through the medium of synchronous selectors, which consists in normally successively selecting in rapid sequence all of the way stations of the system and in simultaneously therewith scanning the indicating message circuits there being only one indicating message circuit for each way station, and in at other times hesitating at a particular way station and during such hesitation in first scanning the indicating message circuit at that way station in then scanning a plurality of control message circuits for said way station.

14. In a centralized traffic controlling system for railroads, the combination with a central office and a plurality of way stations, a track circuit at each of said way stations, signals at each of said way stations, and selector apparatus at said central office and at each of said plurality of way stations effective to normally successively indicate the condition of occupancy of said track circuits and including means to cause said apparatus to hesitate when the condition of occupancy of a particular track circuit is indicated in the event a signal is to be controlled from said central office to permit other selector apparatus to control such signal, and line circuits connecting said selector apparatuses.

15. In a centralized traffic controlling system for railroads, the combination with a central office and a plurality of way stations, a track circuit at each of said way stations, signals at each of said way stations, and selector apparatus at said central office and at each of said plurality of way stations effective to normally successively indicate the condition of occupancy of said track circuits and including means to cause said apparatus to hesitate when the condition of occupancy of a particular track circuit is indicated in the event a signal is to be controlled from said central office to permit other selector apparatus in combination with said first mentioned selector apparatus to control such signal, and line circuits connecting said selector apparatuses.

16. In a centralized traffic controlling sys-

tem for railroads, the combination with a central office and a plurality of way stations, a track circuit at each of said way stations, signals at each of said way stations, and selector apparatus at said central office and at each of said plurality of way stations effective to normally successively indicate the condition of occupancy of said track circuits and including means to cause said apparatus to hesitate when the condition of occupancy of a particular track circuit is indicated in the event a signal is to be controlled from said central office to permit other selector apparatus to control such signal over the same line circuit over which said first mentioned selector apparatus indicates the occupancy of said track circuits.

17. In a centralized traffic controlling system for railroads; the combination with line wires connecting a central office and a plurality of way stations; a track circuit at each way station; selector apparatus for successively indicating the occupancy of said track circuits; a signal associated with each track circuit; a lever in the central office for each signal; separate selector means at the central office and at each way station for controlling the signal at such way station; and means for causing said first mentioned selector apparatus to stop, when the track circuit occupancy at a particular way station is being indicated to allow said other selector apparatus to control the associated signal over a line wire used by said first mentioned selector when the lever for said signal has been placed out of correspondence with such signal, long enough to allow such signal to be controlled.

18. In a centralized traffic controlling system for railroads, the combination with a central office and a plurality of way stations at passing sidings along the railway track, selector apparatus at said central office and at each of said way stations to afford communication between said central office and each of said way stations by establishing such communication with each way station successively once during each cycle of operation of said selector apparatus, and an indicator in said central office for indicating when such cycle has been completed.

In testimony whereof we affix our signatures.

OSCAR H. DICKE.

NEIL D. PRESTON.

DISCLAIMER

1,794,591. *Oscar H. Dicke and Neil D. Preston*, Rochester, N. Y. TRAIN-DISPATCHING SYSTEM FOR RAILROADS. Patent dated March 3, 1931. Disclaimer filed February 16, 1934, by the assignee, *General Railway Signal Company*.

Hereby enters this disclaimer to claims 1, 2, 3, 12, 13, and 18 of said Letters Patent, which are in the following words, to wit:

"1. In a train dispatching system of the synchronous selector wayside signal control type, the combination with a dispatcher's office and a plurality of way stations along the railway track, of a master synchronous selector at the dispatcher's office, a wayside synchronous selector distributed along the railway track, stepping means for operating said synchronous selectors in synchronism to successively complete a large number of message circuits, there being only one OS-ing message circuit and at least one control message circuit for each way station, said stepping means including means for at times setting up successively said OS-ing message circuit only and at other times setting up said OS-ing message circuits and said control message circuits sequentially.

"2. In a train dispatching system of the synchronous selector wayside signal control type, the combination with a dispatcher's office and a plurality of way stations along the railway track, of a master synchronous selector at the dispatcher's office, a wayside synchronous selector distributed along the railway track, stepping means for operating said synchronous selectors in synchronism to successively complete a large number of message circuits, there being only one OS-ing message circuit and at least one control message circuit for each way station, said stepping means including means for at times setting up successively said OS-ing message circuit only and at other times setting up said OS-ing message circuits and said control message circuits sequentially.

"3. In a train dispatching system of the synchronous selector wayside signal control type, the combination with a dispatcher's office and a plurality of way stations along the railway track, of a master synchronous selector at the dispatcher's office, a wayside synchronous selector distributed along the railway track, stepping means for operating said synchronous selectors in synchronism to successively complete a large number of message circuits, there being only one OS-ing message circuit and at least one control message circuit for each way station, said stepping means including means for at times hurdling some of said control circuits but not hurdling any of said OS-ing message circuits."

"12. A method of train dispatching including the control of switch machines and signals from a dispatcher's office and the indication of distant track circuit occupancy in said dispatcher's office through the medium of synchronous selectors, which consists in normally scanning all indicating message circuits sequentially in rapid succession of a synchronous selector system; and in at other times hesitating at a particular indicating message circuit and during such hesitation scanning a plurality of control message circuits in rapid succession.

"13. A method of train dispatching including the control of switch machines and signals from a dispatcher's office and the indication in the dispatcher's office of track circuit occupancy of distant track circuits through the medium of synchronous selectors, which consists in normally successively selecting in rapid sequence all of the way stations of the system and in simultaneously therewith scanning the indicating message circuits there being only one indicating message circuit for each way station, and in at other times hesitating at a particular way station and during such hesitation in first scanning the indicating message circuit at that way station in then scanning a plurality of control message circuits for said way station."

"18. In a centralized traffic controlling system for railroads, the combination with a central office and a plurality of way stations at passing sidings along the railway track, selector apparatus at said central office and at each of said way stations to afford communication between said central office and each of said way stations by establishing such communication with each way station successively once during each cycle of operation of said selector apparatus, and an indicator in said central office for indicating when such cycle has been completed."
